UNITED STATES PATENT OFFICE.

JOHN D. WARREN, OF CHICAGO, ILLINOIS.

DESIGN FOR A SCREW CASE OR CABINET.

SPECIFICATION forming part of Design No. 25,732, dated June 30, 1896.

Application filed April 20, 1896. Serial No. 588,390. Term of patent 3½ years.

To all whom it may concern:

Be it known that I, JOHN D. WARREN, a citizen of the United States, residing at Chicago, Cook county, State of Illinois, have invented and produced a new and original Design for Screw-Cases, of which the following is a specification, reference being had to the accompanying drawing, forming a part thereof.

10 The drawing is a perspective view of my design for the ornamental beading, as shown, forming the border of the case for holding screws.

15 The leading feature of my design is a box having a number of drawers, each of which is provided with a plain panel surrounded by a border of cubes, also forming an ornamental beading, as shown.

1 represents the box, provided, as shown in the drawing, with a number of drawers, the front of each drawer having a plain panel 2, surrounded by a border 3, composed of a series of small cubes. The front of each drawer is provided with a strap 4.

The box has a top 5 with a border 6 of depending V-shaped projections.

I claim as my invention—

The design for a screw-case substantially as herein shown and described.

JOHN D. WARREN.

In presence of—

E. S. KNIGHT,
N. FINLEY.
